UNITED STATES PATENT OFFICE

2,165,067

COMBINATION LOCK

John Pfendner, Chicago, Ill.

Application January 3, 1939, Serial No. 249,037

21 Claims. (Cl. 70—214)

This invention relates to a combination lock which is adapted for various uses, such as, for example, to lock steering wheels of vehicles, safe and vault doors, strong box covers, and the like.

5 The main object of the invention is to provide a combination lock which cannot be unlocked by anyone who does not know the combination and which is so constructed that the combination cannot be ascertained by manipulation of the parts.

10 Another object is to produce a combination lock provided with novel means to be actuated manually for operating the locking means, said manually actuatable means consisting of ten depressible keys marked 1, 2, 3, 4, 5, 6, 7, 8, 9 and 0, respectively, a certain number of which must be actuated, successively, in the order in which they appear in the combination selected, to operate the lock, both for locking and unlocking the parts.

15 In the embodiment of the invention herein shown and described, I have designed the parts for a four digit combination, and the lock shown may be set for any combination of numbers between 0000 and 9999. To lock or unlock the parts, the user must depress, successively, four keys corresponding to the four digits of the selected combination. However, the lock may be designed for combinations other than four digit numbers, as will be made clear in the following specification, and such changes are within the scope of my invention.

20 Another object of the invention is to produce a lock which may be set by the owner to respond to a combination selected by him, and in which the parts thus set are inaccessible excepting to one who knows the combination and first unlocks the lock and then disassembles certain parts to expose the combination setting means. 25 The lock cannot be disassembled before certain parts have been unlocked by actuating the keys which correspond with the numbers of the combination.

25 Actuation of a wrong key, or of a greater or lesser number of keys than called for by the combination, or of the right keys in the wrong order, or simultaneously, will not operate the lock and will not enable the operator to either lock or unlock it.

30 The drawings show my combination lock as embodied in a steering wheel for the purpose of locking the wheel and steering column together, but the lock may be used for locking parts other than steering wheels.

35 The construction of the several parts of my

lock will be described first and then the operation of the parts will be explained.

In the drawings:

Fig. 1 is a plan view of my combination lock, embodied in a steering wheel.

Fig. 2 is a plan view of the lock, with the cover plate removed.

Fig. 3 is a vertical sectional view taken in the plane of the line 3—3 of Fig. 2.

Figs. 4, 5, 6 and 7 are horizontal sectional views taken in the planes of the lines 4—4, 5—5, 6—6 and 7—7, respectively, of Fig. 3.

Fig. 8 is a bottom plan view of the lock supporting plate and parts, taken in the plane of the line 8—8 of Fig. 3, looking upwardly.

Fig. 9 and 10 are perspective views of part of the mechanism shown in Fig. 2, in different positions.

Fig. 11 is a perspective view of another part of the mechanism shown in Fig. 2.

Fig. 12 shows perspective views of disassembled parts of Figs. 9, 10 and 11, namely, the button operating levers.

Fig. 13 is an enlarged sectional view taken in the plane of the line 13—13 of Fig. 5.

Fig. 14 is a transverse section taken in the plane of the line 14—14 of Fig. 13.

Fig. 15 is a plan view of the pulling ring shown in perspective in Figs. 9, 10 and 11.

Fig. 16 is an enlarged elevation of part of the combination transfer ring, shown in plan in Fig. 21.

Fig. 17 is a plan view of the combination setting ring.

Fig. 18 is a sectional view, on the line 18—18 of Fig. 17.

Fig. 19 is an enlarged sectional view, taken in the plane of the line 19—19 of Fig. 17, showing one of the combination setting devices.

Fig. 20 is an end view of the parts shown in Fig. 19, as viewed from the line 20—20 on Fig. 19.

Fig. 21 is a plan view of the combination transfer ring.

Fig. 22 is a vertical section taken in the plane of the line 22—22 of Fig. 21.

Figs. 23 and 24 are perspective and bottom views, respectively, of a lock nut.

Fig. 25 and 26 are perspective and top plan views, respectively, of the combination unlock-ring.

Fig. 27 and 28 are perspective and top plan views, respectively, of the combination lock ring.

Fig. 29 is a perspective view of the combination transfer ring.

- Fig. 30 is a perspective view of the combination setting ring and setting devices.
- Figs. 31 and 32 are perspective and bottom plan views, respectively, of the transfer ring.
- 5 Fig. 33 is a sectional view, taken in the plane of the line 33—33 on Fig. 31.
- Fig. 34 is a perspective view of the lock base.
- Fig. 35 is a perspective view of the locking bolt member.
- 10 Fig. 36 is an elevational and sectional view, showing the parts of Figs. 31, 25, 26, 29, 34 and 35 assembled.
- Fig. 37 is a vertical sectional view and Fig. 38 is a horizontal sectional view taken in the planes 15 of the lines 37—37 and 38—38, respectively, on Fig. 36.
- Fig. 39 shows the assembly of Fig. 36 but viewed from a different position.
- Fig. 40 is a perspective view of the lock nut 20 bolt.
- Fig. 41 is a perspective view of the transfer ring operating knob, bottom side up.
- Fig. 42 is an enlarged perspective of a cam and locking tooth which is part of the mechanism 25 shown in Figs. 36, 37 and 38.
- In that embodiment of the invention shown in the drawings, the steering wheel 45 has a conventional housing 46 mounted in its center, in which is mounted my lock mechanism. The 30 housing 46 is rotatably mounted on a sleeve 47 which is integral with or rigidly and permanently secured to the steering column 48. The sleeve 47 has a grooved collar 49 in which are ball bearings 50 and the bottom of the housing 46 rides on the ball bearings in said collar 49. The sleeve 35 47 has teeth 51 on its upper edge. The dotted lines 52 and 53 indicate the complementary shape of the top of the steering column 48 and part of the sleeve 47 when they are not made integral, 40 but are fitted together and rigidly connected together.
- A fibre packing 54 is located between the steering post 55 and column 48. On the steering post 55 is a key 56 which fits into a keyway 57 in the 45 hub 58 of the lock base 59. The parts 58 and 59 are integral, as shown in Fig. 34. As shown in Fig. 3, the upper end of the steering post 55 is tapered so that the hub 58, also internally tapered, fits on the tapered part of the post 55 50 and on the key 56, and is held immovably on the post. The bottom of the lock base has a depending, square housing 60 which fits into the square opening in the bottom of the supporting plate 61 which rests on the bottom 62 inside of the 55 steering wheel housing 46, as shown in Figs. 3 and 8. The lock base 59 is screwed to the plate 61 and bottom 62 by screws 63. The square housing 60 on base 59 protrudes below the housing bottom 62.
- 60 The hub 58 of the lock base 59 has formed on its outer surface two guideways 64 opposite each other, said guideways extending downwardly through the offset 65 to receive the arms 66 of a toothed locking bolt member 67. The arms 66 65 are arcuate in cross section to fit against the walls of the hub 58 and slide in the guideways 64. The bolt member 67 has a square base which fits within the housing 60 formed on the bottom of the lock base 59. Said square base 67 has teeth 68 on its bottom surface which mesh with the teeth 51 of the sleeve 47 on the column 48 when the steering wheel is locked. The bolt member 67 has a keyway 69 to permit the member 67 to be mounted on the post 55 by slipping over the key 56. The bolt member 67 is movable ver-
- tically in the stationary lock base 59 and on hub 58, to move the teeth 68 into and out of engagement with the teeth 51 of the sleeve 47, as will be more fully explained.
- In the offset part 65 of the lock base 59 is 5 mounted a spring pressed cam and lock tooth 70, best shown in Figs. 34 and 42. It consists of a shank having a lock tooth 71 and cam 72, the shank part being mounted in a hole in the part 65 of the lock base 59, with a coiled spring bearing 10 against the under side of the cam 72. A brake 74 is attached to the lock base 59, as indicated in Fig. 5.
- In Figs. 29, 36—39 is shown a combination transfer ring 75 which bears on the groove 65' 15 of the part 65 of the lock base 59 and is rotatable on said base. It has a coiled spring 76 secured to the under side of the ring and to the base 59. A cam 77 projects inwardly from the grooved top wall of the ring 75, for sliding over the cam 20 surface of the cam 72, to depress the cam and release the tooth 71 for a purpose to be explained. The vertical part of the ring 75 has formed on its lower edge five teeth 78. Pins 79 project upwardly from the top of the ring 75, 25 for positioning a combination setting ring 80 (Figs. 17 and 30).
- The combination setting ring 80 has 40 holes 81, and intermediate the holes are radial grooves 82. The 40 holes are divided into ten groups, 30 each group being numbered from 1 to 4, inclusive. This particular combination setting ring 80 is arranged for a four digit combination, with a choice of any numbers between 0000 and 9999. These ten sets of numbers are located adjacent 35 the inner edge of the ring and the numbers 1 to 4 of each set run anti-clockwise. Another set of numbers appears adjacent the outer edge from 1 to 9, inclusive, and 0, and these run clockwise.
- Four combination setting devices are identical, 40 and one is best shown in Figs. 19 and 20. It consists of a rectangular housing 83 having two upright apertured arms 84. A shaft 85 having a lever 86 is mounted rotatably in the apertured arms 84. A spring 87 is coiled on the shaft 85 45 and has one end connected to the top of the lever 86 and the other end bears on the middle of the top of a drop lever 88 which is pivoted at 89 to the housing 83. The free end of the drop lever 88 moves in a slot 90 in the housing. Fixed on the end of the shaft 85 is a hooked lever 91 for 50 engaging the drop lever 88 and holding it up until the lever 86 is swung from the solid line position to the dotted line position of Fig. 20, as will be explained in the explanation of operation. 55 The housing 83 is connected to the combination setting ring 80 by means of a bolt 92 rigidly connected to the bottom of the housing 83 and extending through the ring 80 and held by a nut 93. Each combination setting device 83 is seated 60 in a groove 82 on the ring 80. The positioning of the several devices 83 for setting the combination will be fully explained later.
- The ring 80 has two small gauging holes 94, 65 one near the outer edge and the other near the inner edge, for engagement with the pins 79 on the ring 75 when the two rings are assembled and screwed together by screws which extend through some of the holes 81 in ring 80 and registering holes 95 in the ring 75.
- 70 Before the ring 80 is mounted on the ring 75, I position on the shoulder 65 of the lock base 59, a combination lock ring 96 (Fig. 27) which is screwed tightly on said base 59, and slightly overlies the combination transfer ring 75 and holds it 75

down on the lock base 59—65, but permits said ring to rotate. The lock ring 96 has a square notch 97 cut in its bottom flange 98 (Fig. 28) to accommodate the lock tooth 71 of the spring 5 pressed member 70 located in the lock base 59—65. Said bottom flange 98 is slotted at 99, and the vertical wall of the ring 96 has ten uniformly spaced notches 100 on its upper edge, one edge of each notch being perpendicular and the other edge extending at a 45° angle.

In Figs. 25, 36-39 is shown the unlock ring 101 which has on the under side of its narrow bottom flange 102 a pin 103, which pin extends into the slot 99 of the lock ring 96 when the unlock ring 101 is placed within the ring 96. On the upper surface of the bottom 102 is a pin 104. Said bottom flange 102 is cut away at 105 to accommodate the member 70 when the parts are assembled. The pin 103 of ring 101, moving in the slot 99 of ring 96, limits the movement of the ring 101. The ring 101 has ten cam shoulders 106 on its upper edge.

A transfer ring 107 (Fig. 31) surrounds the hub 58 of the lock base 59, also the arms 66 of the locking bolt member 67 (the arms being in the guideways 64 of the hub 58), and a lock nut bolt 108 which fits and moves vertically between two ribs 109 on the hub 58 of the lock base 59. The transfer ring 107 has on its bottom two radial grooves 110, which alternately engage the tooth 71 to prevent turning of the transfer ring as long as said tooth 71 is engaged. On the circumferential wall of the ring 107, near the bottom, is a flange 111 cut away at 112, the cut away part accommodating the pin 104 on the unlock ring 101. Thus the transfer ring 107 can turn in the unlock ring 101 a distance as long as the cut away part 112 into which the pin 104 extends, and after the transfer ring 107 has come into contact with the pin 104 at the end of the initial movement, then the continued turning movement of the transfer ring 107 moves the unlock ring 101 in the lock ring 96 a distance equal to the length of the slot 99 into which the pin 103 extends. At the end of said movement, the transfer ring is locked by the tooth 71 entering one of the grooves 110 in the ring 107.

The transfer ring 107 has in its circumferential wall two oppositely inclined and oppositely positioned cam slots 113, and a third inclined slot 114. When the transfer ring 107 has been placed over the hub 58, arms 66 and bolt 108, screws 115 are screwed into the holes 116 in the arms 66, with the heads of the screws located in the slots 113. (See Figs. 36-39.) The pin 117 on the bolt 108 extends outwardly through the slot 114. When the transfer ring is rotated manually, the screw heads 115 on the arms 66 travel in the cam slots 113, and cause the arms 66 to be moved upwardly or downwardly, depending on which way the ring 107 is being turned, and move the teeth 68 of lock bolt member 67 into or out of mesh with the teeth 61. This same movement of the transfer ring 107 moves the lock pin bolt 108 in the opposite direction to that of the arms 66, due to the engagement of the pin 117 in slot 114.

The top of the transfer ring 107 has two recesses 118 which register with lugs 119 on the bottom of the transfer ring operating knob 120. A cover 121, centrally apertured to fit on the transfer ring, is held down on said ring, under the operating knob 120, by a lock nut 122 which is screwed on the steering wheel post 55. The nut 122 holds the knob 120 and cover 121 tightly down against the hub 58 of the lock base 59 on the

tapered end of the steering post 55, the operating knob 120 and transfer ring 107 being rotatable by reason of the engagement of the lugs 119 of the knob in the recesses 118 of the transfer ring 107.

The lock nut 122 has two wrench holes 123 extending vertically through the nut and a countersunk hole 124 to receive a screw for fastening the nut 122 to the hub 58 after the nut 122 has been screwed tightly on the steering wheel post, to insure immobility of the nut 122. On the under side of the nut 122 is an offset, notched at 126 to receive the top of the lock bolt 108 in one of the notches. The nut 122 cannot be turned to remove it until the locking parts are unlocked and the bolt 108 is in its downward position by the turning of the transfer ring.

A series of ten buttons 130 is shown (Figs. 1-12). They are identical except that they are numbered 1 to 9 inclusive, and zero, respectively. The construction of one button will be described. It comprises a hollow stud 131 fixed on the base 61 of the housing. Inverted cup members of two diameters 132, 133, are connected together so that the smaller one is sleeved on 25 the stud 131 and the large part forms a button to be depressed by the fingers. Within the stud is a spring 134 which normally holds the button members 132 and 133 in raised position. The cover 121 has ten guards 135, cylindrical in 30 shape, and slotted to allow lever operating pins 136 on the buttons to move up and down in the guards in vertical paths, when the buttons are depressed.

Also on the base plate 61, between adjacent buttons 130, is a series of lever supporting posts 137. A slotted bell crank lever 138 is pivotally mounted at 139 on the post 137 by screw and nut 140. The pin 136 extends through the slotted end of lever 138. Said lever is bent at 141 to 40 accommodate the form of the button. On the other end of the lever 138 is pivotally connected a pulling hook 142 which engages a slotted pulling ring 143 having slots 144, one for each pulling hook for each button. The lever 138 has a stop 45 145 formed as shown in Fig. 12 which prevents the operator from depressing adjacent buttons. 146 is a stop on the post 137 for the lever 138.

The pulling ring 143 has a horizontal bottom flange which has slots 147 into which extend pins 148 fixed in the plate 61. Springs 149 are attached to the side wall of the ring 143 at 150 and to the pins 148. The upright wall of the ring 143 has ten of the slots 144, through which the pulling hooks 142 extend and either pull the ring or slide in the slots. The ring 143 is held down on the base plate 61 by screws 151 which extend through slots 147 so that the pulling ring 143 can be rotated a slight distance in one direction and is automatically returned by the springs 149. 60

On the inner vertical wall of the pulling ring 143 is attached a cam lever 152 pivotally mounted at 153. The lever 152 has on its free end a pawl or cam 154 and on its side a transfer pin 155. A spring 156, attached to the pulling ring wall 143, bears down on the cam lever 152 and when the pulling ring is moved from left to right (Fig. 13) by pressing a button 130, the cam 154 drops from the slot 157 in the bottom wall of the pulling ring 143 into a longer slot 158 in the base plate 61. When the lever is in said lowered position, the transfer pin 155 engages the first of the teeth 78 and thus moves the combination transfer ring 75 one-fortieth of its periphery, clockwise.

To assemble the parts heretofore described, the buttons 130 and their levers 138 and pulling hooks 142, with the lever supports 137, are mounted on the base plate 61 within the housing 51. The pulling ring 143 is mounted on said base just inside of the buttons (Figs. 9-12), the ring 143 having limited rotative movement on the base 61. The base 61 is screwed to the base 62 which is rigidly connected to the housing 46. The lock bolt member 67 is inserted into the lock base 59, with the arms 66 in the guideways 64 and the keyway 69 aligned with the keyway 57 on the inside of the hub 58. Next the lock base 59 is positioned with its square housing 60 protruding through the square openings in plates 60 and 61, and then the lock base 59 is screwed down securely on said plates by screws 63. The cam and tooth member 70 is mounted in the part 65 of the lock base 59 as shown in Fig. 34, with a coiled spring 73 normally holding the cam 72 and tooth 71 in upward position. Then the combination transfer ring spring 76 is connected to the ring 75 on its inner side wall and the other end is connected to a hook 159 on the lock base 59 (see Fig. 34), and the ring 75 is placed down on the lock base 59—65, with the cam 71 resting in the curved groove 160 which limits the movement of the combination transfer ring 75.

Then the lock ring 96 is positioned on the lock base 59 so that the tooth 71 of the member 70 registers with and projects upwardly through the notch 97 in the bottom of the lock ring 96. The ring is then screwed down on the base 59, by countersunk screws. The lock ring 96 holds the transfer ring 75 and member 70 down on the base lock 59—65 without interfering with the rotation of the combination transfer ring 75.

Next the unlock ring 101 is loosely placed within the lock ring 96, with the pin 103 in the slot 99 of the lock ring 96, so the unlock ring 101 can rotate to the extent of the slot 99.

The lock nut bolt 108 is placed against the inside of the transfer ring, with the pin 117 projecting outwardly through the slot 114. Then the transfer ring 107 and bolt 108 are placed over the hub 58 of the lock base 59, with the bolt 108 between the ribs 109, as shown in Fig. 39, and with the cut away part 112 of the flange 111 positioned to receive the pin 104 on the unlock ring 101, so that when the transfer ring 107 is rotated, it can move a certain distance independently and later moves the unlock ring 101 with it, when the pin 104 engages the flange 111 at the end of the cut away part 112. The screws 115 are screwed into the holes 116 in the arms 66 of the lock bolt member 67, with the heads of the screws in the slots 113 in the transfer ring 107. This allows the transfer ring to be turned relatively to the hub 58, a distance limited by the length of the slots 113, and the turning of the ring 107 thus raises or lowers the toothed member 67 by the arms 66.

Next the combination setting ring 80 is placed over the combination ring 75, but before doing so, the setting devices 83 are positioned on the ring 80 according to the selected combination. In the drawings, I have shown the lock set for the combination 1876. We will refer to the four digits of the combination as the first, second, third and fourth numbers. If the first number happens to be "1", then the setting device 83a is placed over the hole marked "1" in the section marked for button "1". If the second num-

ber is "8", then another setting device, 83b, is placed over the hole marked "2" in button number "8" section. If the third number is "7", then another setting device, 83c, is placed over the hole marked "3" in the section for button "7". If the fourth digit is "6", then another setting device, 83d, is placed over the hole marked "4" in the section for button "6". The numbers on the ring 80 near the outer edge are the ten button numbers, running clockwise, and the ten groups of numbers, 1 to 4, near the inner edge, indicate the order of the digits of the combination, and run counter-clockwise. In Fig. 17, the four setting devices 83 are shown as set for the combination 1876. The bolts 92 extend through the holes 81 and a rib on the bottom of the device housing 83 fits in a groove 82 on the ring 80, to hold the setting devices in position when the nut 93 is tightened.

The combination setting ring 80, with setting devices 83 in place, is then positioned on the combination transfer ring 75, with the pins 79 fitted into the registering holes 94 in ring 80. Screws are used to fasten the two rings together, by using any three or four free holes 81 and registering holes in the ring 75. See Fig. 2, indicating the positions of the devices 83 relatively to the buttons 1, 8, 7 and 6 which must be operated for this combination, as will be explained.

Next the steering wheel with housing 46 and lock parts assembled therein are placed over the steering post 55, with the keyway 57 of lock base hub fitting on key 56 on the steering post, the bottom of the housing fitting into the grooved collar 49. The cover 121 is placed over the top of the housing, with the guards 135 around the buttons 130. The cover is pushed down, as shown in Fig. 3, and then the transfer ring operating knob 120 is positioned with its lugs 119 engaging the recesses 118 of the transfer ring 107. Then the lock nut 122 is screwed on to the top end of the steering post 55 and bears down on the knob 120 and housing top 121, and holds the housing firmly against the balls in the collar 53. The lock nut bolt 118 engages one of the notches 126 on the bottom of the lock nut 122, when it has been screwed down, and thereafter a screw may be placed in the hole 124 to connect the lock nut to the top of the hub 58.

Finally, a horn button 161 and a threaded ring 162 are placed as shown in Fig. 3. The ring holds the horn button on the lock nut.

When assembled as described, the mechanism cannot be disassembled while locked because the lock nut bolt 108 is in its upward position, engaging one of the notches 126 on the under side of the lock nut 122. To move the bolt 108 out of engagement, it is necessary to unlock the lock by means of the combination, and then manually turning the transfer ring operating knob 120 clockwise.

Assume the lock to be unlocked, and the teeth 51 on the steering column and teeth 68 on the lock bolt member 67 to be out of mesh as shown in Fig. 3. In that position, the arms 66 are in their uppermost position in the hub 58, as in Fig. 3. To lock the mechanism, the buttons corresponding to the combination numbers must be pressed downwardly, successively, in the order of the number.

The operation of a button will now be described. When a button 130 is depressed fully, it has moved $\frac{1}{16}$ ". Pressing of a button causes the pulling ring 143 to be rotated by the lever 138 75

and pulling hook 142. This movement causes the cam lever 152 to drop into the slot 158 and at the same time the pin 155 engages the first one of the teeth 78 on the combination transfer ring 75, 5 and moves it and the combination setting ring 80 one-fortieth of their circumference, clockwise. Assuming the correct button has been operated, that is, the first of the numbers of the combination, the device 83a will move past the lever operating pin 136 of the pressed button, and the lever 86 will be swung from left to right, releasing the hook lever 91, and allowing the drop lever 88 to engage a notch 100 in the lock ring 96. This will be understood by reference to Fig. 2, where button numbered 1, if pressed, will move the rings 15 and 80, as explained, and thereby move the device 83a to the pin 136 on button 1, and as the pin moves down with the button, the lever 86 on device 83a is swung, as explained, to move the drop lever 88 into a notch of the lock ring 96. 10 The other three combination devices, 83b, 83c and 83d, will also have been moved with the ring 80 one step nearer their buttons.

The combination transfer ring 75 and other parts mentioned will be held in the advanced position by the drop lever 88, ready for the next button movement, but as soon as the depressed button is released, the pulling ring automatically returns to its normal original position and pin 30 155 is released from the tooth 78.

When the second button, in this case button 8, is depressed, the same movement of the pulling ring 143 takes place as before, but this time the pin 155 on cam lever 152 engages the second tooth 78 on ring 75, moving the combination transfer ring 75 a second step, clockwise. This causes the drop lever of device 83a to move up on the 45° edge of the notch 100 in ring 96 and allows the hook lever 91 to re-engage the drop lever and hold it in raised position, out of the notch of the ring 96; and at the same time, the device 83b will be moved opposite button 8 and drop lever 88 of device 83b will drop into a notch of the ring 96 and be held there until the third button is depressed. The same cycle of movements will take place when the third button, in this case button 7, and the fourth button, in this case button 6, are successively depressed. It will be understood that the devices 83c and 83d will have been moved 40 from the positions shown in Fig. 2 to positions opposite their respective buttons as heretofore explained in connection with the other two devices, 83a and 83b.

When the fourth step or advance of the combination transfer ring 75 has taken place, by depressing the fourth button of the combination, the cam 77 on the inner edge of ring 75 will have moved from the position shown in Fig. 5 to a position where it contacts with the cam 72 of the member 79, thereby depressing the member 70 and releasing the tooth 71 from the groove 110 of the transfer ring 107, thereby allowing the transfer ring 107 to be turned manually by means of the operating knob 120. In locking the lock, the knob 120 is turned counter-clockwise, thereby moving the arms 66 downwardly in the hub 58, and meshing the teeth 68 with teeth 51 on the steering column sleeve 47. The same movement of the transfer ring 107 by the knob 120 moves the lock nut bolt 108 upwardly into a notch 126 on the lock nut 122, and when the transfer ring flange 111 engages the pin 104 on the unlocking ring 101, it carries the unlock ring with it a short distance, so that the cam edges 106 lift up the 50 drop lever of the device 83d, and the combination

transfer ring 75 and ring 80 return to original position, where the transfer ring 107 is engaged by the tooth 71 in one of the grooves 110 and again held in stationary position.

To unlock the lock, the buttons corresponding with the combination numbers must be depressed, successively, in the order of the number; then the operating knob must be turned clockwise, which moves the transfer ring 107 also clockwise, pulls the arms 66 upwardly and moves the teeth 68 10 out of mesh with the teeth 51.

Assume that one, two or three of the buttons have been correctly operated and that then a wrong button is depressed. The effect of this will be that the drop lever of the last device 83 previously operated will be raised by moving out 15 the notch of the locking ring 96 and since the wrong button will not operate any device 83, there will be nothing to hold the combination transfer ring 75 and it will return to original position by reason of the spring 76. 20

Even if the four buttons of the combination have been correctly depressed, and a fifth button is then depressed, the combination transfer ring 75 will be moved a fifth step by the cam lever 152 engaging the fifth button 18 on ring 75 and that step will cause the drop lever of the fourth device 83d to be raised by moving out of the notched ring 96, and being held raised by its hook lever 91, the ring 75 will be released and return 30 to original position.

To enable the owner to change the combination, he must unlock the mechanism by means of the right combination buttons and by operating the knob 120; then he can remove the lock nut 122 and the housing cover 121 and can take out the screws which hold the combination setting ring 80 on the combination transfer ring 75, remove the ring 80, and reset the devices 83 as he desires. 40

The buttons cannot be depressed simultaneously because the stop 145 on the elbow lever 138 prevents an adjacent button from being fully depressed. (See position of button 8 in Fig. 10.)

The brake 74 on lock base 59 engages the inside 45 of the combination transfer ring 75 near the end of its return movement and prevents the cam 77 of the ring 75 from hitting hard the wall at the end of the recess 160 when the ring 75 returns to original position under power of spring 76. 50

The cam and tooth member 70 is referred to in the claims as a "retaining member" because it prevents rotation of the manually operable transfer ring 107 on the base 59.

Changes may be made in details of construction and adaptation of the lock to devices other than steering wheels, without departing from the scope of my invention. 55

I claim:

1. A combination lock comprising cooperating locking members at least one of which is movable relatively to the other to lock and unlock said members, a housing for the movable member, a series of depressible buttons mounted in the housing, and operative connections between said buttons and the movable cooperating locking member, said movable member being actuatable, alternately, to locked position by depressing certain predetermined buttons and to unlocked position by depressing the same buttons. 60

2. A combination lock comprising a fixed locking member, a housing rotatably mounted on the fixed locking member, an axially movable locking member mounted in the housing to rotate with the housing, a series of depressible buttons 75

mounted in the housing, and operative connections between the buttons and the movable locking member for actuating said member, said movable locking member being actuatable by depressing and releasing a plurality of said buttons, successively, in predetermined order.

3. A combination lock comprising a housing, a locking bolt movably mounted in the housing, a plurality of depressible buttons in the housing, and operative connections between the buttons and said movable locking bolt for actuating the bolt, said operative connections comprising a combination transfer ring, means operable by said buttons for moving the ring rotatively, step by step, means for holding the combination transfer ring in advanced position, a manually movable transfer ring connected to the locking bolt, and retaining means for holding the transfer ring immovable, said retaining means being releasable by said combination transfer ring when in advanced position, to permit manual movement of said transfer ring and locking bolt.

4. A combination lock comprising a housing, a locking bolt movably mounted in the housing, a plurality of depressible buttons in the housing, and operative connections between the buttons and said movable locking bolt for actuating the bolt, said operative connections including a lever operating pin on each button.

30. 5. A combination lock comprising a housing, a locking bolt movably mounted in the housing, a plurality of depressible buttons in the housing, and operative connections between the buttons and said movable locking bolt for actuating the bolt, said operative connections comprising a pulling ring, a fixed support adjacent each button, a bell crank lever pivotally mounted on each support, a hook on each of said levers engaging the pulling ring, and a lever operating pin on each button for actuating the lever and pulling ring.

40. 6. A combination lock comprising cooperating locking members at least one of which is movable relatively to the other to lock and unlock said members, a housing for the movable member, a series of depressible buttons mounted in the housing, a lock base and hub fixedly mounted in the housing, said movable cooperating locking member being axially slidable in said base and hub, a manually rotatable member on the hub connected to the movable cooperating locking member, retaining means between the lock base and manually rotatable member for preventing rotation of said member, and operative connections between said buttons and said retaining means for releasing said retaining means and permitting manual rotation of said rotatable member, said rotatable member being actuatable by depressing and releasing a plurality of said buttons, successively, in predetermined order.

60. 7. A combination lock comprising a housing, a series of depressible buttons in the housing, a combination transfer ring rotatably mounted in the housing and actuated by said buttons, a lock base and hub fixed in the housing, an axially movable lock bolt member in the hub, a cam slotted transfer ring rotatable on the hub and rotatably secured to the lock bolt member, and retaining means between the lock base and said cam slotted transfer ring, actuated by said combination transfer ring, retaining the cam slotted transfer ring immovably on said lock base.

70. 8. A combination lock comprising a housing, a series of depressible buttons in the housing, a combination transfer ring rotatably mounted in the housing and actuated by said buttons, a lock

base and hub fixed in the housing, an axially movable lock bolt member in the hub, a cam slotted transfer ring rotatable on the hub and rotatably secured to the lock bolt member, retaining means between the lock base and said cam slotted transfer ring, actuated by said combination transfer ring, and a manually operable knob on the cam slotted transfer ring for rotating said ring when the retaining means has been released by the rotation of the combination transfer ring. 10

9. A combination lock comprising a housing, a series of depressible buttons in the housing, a fixed support adjacent each button, a bell crank lever pivotally mounted on each support and connected with a button, a pulling ring rotatably mounted in the housing, means on each bell crank lever engaging the pulling ring, a combination transfer ring rotatable in the housing, a combination setting ring connected to the combination transfer ring, means on the pulling ring for engaging the combination transfer ring and rotating it in a step by step movement, a locking ring, means on the combination setting ring for engaging the locking ring and holding the combination transfer ring in advanced 20 position when certain buttons have been actuated, and an unlocking ring within the locking ring.

10. A combination lock comprising a housing, a locking bolt movably mounted in the housing, a series of buttons depressibly mounted in the housing, operative connections between the buttons and said locking bolt, and means for preventing simultaneous actuation of adjacent buttons. 30

11. In a combination lock, a rotatably mounted combination setting ring and a series of numbered buttons, the combination setting ring being marked to indicate uniform circumferential sections corresponding to the said buttons, and each of said sections being marked to indicate uniformly spaced portions of each section equal in number to the digits of the combination. 35

12. In a combination lock, a rotatably mounted combination setting ring and a series of numbered buttons, the combination setting ring being marked to indicate uniform circumferential sections corresponding to the said buttons, and each of said sections being marked to indicate uniformly spaced portions of each section equal in number to the digits of the combination, one of said series of markings being located adjacent the periphery of the ring and the other series of markings being located adjacent the inner edge of the ring and running counter to the first 50 mentioned markings. 55

13. In a combination lock, a series of depressible buttons numbered 1 to 9, inclusive, and zero, a rotatably mounted combination setting ring provided with equi-distantly spaced holes equal in number to ten times the digits of the combination selected, said ring being marked to indicate ten equal groups of holes, corresponding with the button numbers, respectively, and the holes of each group being numbered successively, from one to the number of digits in the combination. 60

14. In a combination lock, a combination setting ring, setting devices secured to said ring in selected positions, a locking ring adapted to be 70 engaged by said setting devices, depressible buttons, operative connections between the buttons and combination setting ring for rotating the ring, and means on the buttons for engaging the setting devices on the combination setting 75

ring and causing them to engage the locking ring.
 15. In a combination lock, a combination setting ring, a combination locking ring and setting devices located in selected positions on the combination setting ring, said devices comprising a housing, a drop lever pivotally mounted on the housing, a shaft having a hook lever at one end for retaining the drop lever in raised position, and an operating lever on the other end of the shaft for rocking the shaft, releasing the hook lever from the drop lever, and permitting engagement between the drop lever and combination locking ring.

16. A combination lock comprising a housing, a series of depressible buttons in the housing, a combination transfer ring rotatably mounted in the housing and actuated by said buttons, a lock base and hub fixed in the housing, an axially movable lock bolt member in the hub, means actuated by the combination transfer ring for permitting the lock bolt member to be manually moved, means for automatically returning the combination transfer ring to initial position, and a brake between the lock base and combination transfer ring.

17. A combination lock comprising a fixed cylindrical member having teeth on one end, a housing rotatable relatively to the cylindrical member, a lock base and hub fixedly mounted in the housing, a toothed lock bolt mounted in the lock base and hub and movable axially into and out of engagement with the teeth on the cylindrical member, a series of depressible buttons in the housing, and operative connections between the buttons and the toothed lock bolt for moving said member when certain of said buttons have been depressed successively.

18. A combination lock comprising a housing, a locking bolt movably mounted in the housing, a plurality of buttons depressibly mounted in the housing, operative connections between the buttons and the locking bolt including a lateral projection on each button, and a cover closing the housing, said cover having openings in its

face registering with said buttons and guards surrounding said openings, the guards being slotted to accommodate the lateral projections on said buttons.

19. An automobile lock comprising a cup-shaped housing adapted to be mounted concentrically in the steering wheel of an automobile, a plurality of buttons depressibly mounted in the housing and movable in directions parallel with the axis of the wheel, a locking bolt concentrically mounting in the housing, operative connections between the buttons and said locking bolt, and an apertured cover closing the open top of the cup-shaped housing and permitting manual depression of said buttons.

20. An automobile lock comprising a cup-shaped housing adapted to be mounted concentrically in the steering wheel of an automobile, a lock base fixedly mounted in the housing, means on the lock base for non-rotatably mounting it on a steering post, a locking bolt concentrically mounted and axially movable in the lock base, a plurality of buttons depressibly mounted in the housing, operative connections between the buttons and locking bolt, and means on the locking bolt for engaging a fixed cooperating locking member on the steering post column of an automobile.

21. An automobile lock comprising a housing adapted to be mounted concentrically in the steering wheel of an automobile, a toothed cylindrical member adapted to be fixedly mounted on the steering post column of an automobile with the toothed portion extending into the bottom of the housing, a lock base fixed in the housing, means for non-rotatably fixing the lock base to the steering post of an automobile, a toothed locking bolt concentrically mounted and axially movable in the lock base, means for actuating the locking bolt toward and from the toothed cylindrical member, a lock nut adapted to be mounted on the steering post and a lock nut bolt movably mounted in said lock base.

JOHN PFENDNER.
